ENGINE STARTER GEARING

Donald L. Miller, Pine City, N. Y., assignor to Bé-
dix Aviation Corporation, Elmira Heights, N. Y.,
a corporation of Delaware

Application June 21, 1946, Serial No. 678,343

4 Claims. (Cl. 74—9)

1

The present invention relates to engine starter gearing and more particularly to a starter drive which is arranged to yield and disconnect in case of overload.

Various kinds of starter drives incorporating overload release devices have been proposed from time to time, but they have in general been complicated and expensive and/or uncertain in their operation, particularly in respect to maintaining the proper depth of mesh of the pinion with the engine gear.

It is an object of the present invention to provide a novel engine starter drive incorporating an overload release device which is efficient and reliable in operation while being simple and economical in construction.

It is another object to provide such a device in which the operative position of the starting pinion is accurately defined.

It is a further object to provide such a device including an over-running connection between the starting motor and the drive pinion.

It is another object to provide such a device including yielding means for demeshing the drive pinion and maintaining the engagement of the over-running clutch connection.

It is another object of the invention to provide a device in which all the parts of the drive are so mounted and piloted on the drive shaft that proper alignment of the parts is maintained at all rotative speeds.

Further objects and advantages will be apparent from the following description taken in connection with the accompanying drawing in which:

Fig. 1 is a side elevation partly broken away and in section of a preferred embodiment of the invention, showing the parts in idle position; and

Fig. 2 is a similar view showing the parts in operative position.

In Fig. 1 of the drawing there is illustrated a starting motor 1 having a smooth extended armature shaft 2 on which a drive pinion 3 is slidably journaled for movement into and out of mesh with a gear 4 of an engine to be started.

Means for actuating the pinion from the drive shaft 2 is provided comprising a driving head 5 rigidly mounted adjacent the outer end of the drive shaft by suitable means such as a cross pin 6. The drive head 5 is provided with ratchet teeth 7 adapted to engage corresponding teeth 8 of a driving cam member 9 which is freely journaled on the drive shaft 2. A driven cam member 11 similarly mounted on the drive shaft is arranged to cooperate with the driving cam member 9. Cam member 11 has a flanged sleeve

2

13 suitably fixed thereon as by welding or brazing as indicated at 12, which sleeve forms a seat for one end of a yielding driving member 14 in the form of a cylinder of elastically deformable material such as rubber.

The opposite end of the yielding driving member 14 bears frictionally on a thimble 15 having a telescopic bearing on the sleeve 13, and rigidly attached as by welding or brazing at 16 to a flange 17 fixed as indicated at 18 to the pinion 3.

A barrel member 19 is arranged to surround and enclose the yielding drive member 14, and is provided with an internal groove 21 receiving the peripheries of thimble 15 and pinion flange 17, which are retained in the groove 21 by spinning over the end of the barrel as shown at 22.

The barrel 19 is journaled at an intermediate portion on the flange 23 of sleeve 13, the barrel being provided with a shoulder 24 forming an abutment for the flange so as to maintain the yielding driving member 14 under initial compression. The barrel has a rearwardly extending portion 25 which is preferably tapered as shown, and terminates in a radially inwardly extending flange 26 which bears on the driving shaft 2 and is adapted to engage the driving head 5 as shown in Fig. 2 in order to limit the longitudinal movement of the barrel and its associated parts and thereby define the operative position of the pinion 3 with relation to the engine gear 4. A hardened insert or washer 27 may be interposed between the flange 26 of the barrel and driving head to reduce wear.

Means for normally maintaining the parts in idle position is provided in the form of a light compression spring 28 seated at one end in the end of the barrel 19 and at its other end on a ring member 29 surrounding the driving head 5 so as to retain the pin 6 in position, and bearing 40 against a shoulder 31 formed on said driving head.

In assembling the drive, the parts, with the exception of the pin 6, are inserted in order through the open end of the barrel 19, and are retained by crimping over the end of the barrel 45 as shown at 22. When the drive is to be mounted on a motor shaft, the assembly is slid on the shaft, a tool is inserted through the opening 32 in the barrel to move back the ring 29, whereupon the pin 6 is passed through opening 32 and 50 through the drive head 5 and shaft 2, and the ring 29 permitted to return to its normal position, thus retaining the pin 6 in locked position.

According to the present invention, the cam members 9 and 11 are provided with cooperating cam surfaces 33, 34 respectively which are so in-

clined to the axis of the power shaft that torque transmitted from the driving cam member 9 to the driven cam member 11 generates an axial component of force tending to move the cam member 11 to the right and thereby compress the yielding driving member 14 as shown in Fig. 2. The height and inclination of the cam surfaces 33, 34 are so coordinated with the elasticity of the yielding member 14, that when a predetermined safe maximum torque value is exceeded, the cam surfaces 33 will slide off the ends of the cam surfaces 34, thereby temporarily breaking the torque connection between the cam members.

In the operation of the device, starting with the parts in the position shown in Fig. 1, energization of the power shaft 2 by the starting motor causes rotation of the driving head 5 to be transmitted through the over-running clutch connection 7, 8 to the driving cam member 9. Rotation of the driving cam member causes longitudinal movement of the driven cam member 11 to the right, thereby moving the barrel assembly including the pinion 3 longitudinally until the pinion is fully meshed with the engine gear 4 at which time the flange 26 of the barrel engages the driving head 5 and thereby arrests the longitudinal movement of the barrel. Further rotation of the power shaft 2 causes compression and torsion of the yielding member 14 until the resistance of the engine gear 4 to rotation is overcome, and the engine is set in motion.

When the engine becomes self-operative, the acceleration of the engine gear 4 causes the pinion 3 with its associated parts to overrun the power shaft 2, which overrunning is permitted by the saw-tooth dental clutch 7, 8. The spring 28 is thereupon operative to withdraw the parts to idle position and thereafter maintain the engagement of the clutch teeth 7, 8.

If the starter should be energized inadvertently at a time when the engine gear is rotating backwardly from a previous start and back-fire, or for any other reason, the collision of the forwardly rotating parts of the starter mechanism with the backwardly rotating engine gear may cause excessive stresses to be developed. Should this occur, the yielding member 14 is further compressed beyond its usual operative position as shown in Fig. 2 until the ends of the driving cam surfaces 33 slip by the ends of the driven cam surfaces 34, so as to release the driving connection and prevent damage to the parts. As soon as the excessive forces have been dissipated, cranking may be resumed in the usual manner until the engine is reliably self-operative.

Although but one embodiment of the invention has been shown and described in detail it will be understood that other embodiments are possible

and various changes may be made in the design and arrangements of the parts without departing from the spirit of the invention as defined in the claims appended hereto:

5. What is claimed is:
1. In an engine starter drive a power shaft, a pinion slidably journaled thereon, a barrel fixed at one end to the pinion and journaled at its other end on the shaft, a driving head in the barrel forming an abutment defining the operative position of the barrel and pinion, a driving cam member on the shaft connected to rotate with the driving head, a driven cam member slidably journaled on the shaft and having an inclined connection to the driving cam member, a compressible driving connection between the driven cam member and pinion and yielding means in the barrel urging the pinion toward idle position.
  2. A starter drive as set forth in claim 1 in which said compressible driving connection is so co-ordinated with the inclined connection between the cam members that the cam members may slip and disengage upon a predetermined overload.
  3. An engine starter drive as set forth in claim 1 including further an over-running clutch connection between the driving head and driving cam member.
  4. An engine starter drive including a power shaft, a driving head fixed thereon, a pinion journaled on the shaft and movable longitudinally into and out of mesh with a gear of an engine to be started, means including an inclined connection and a yielding torque transmitting member for connecting the pinion for actuation by the driving head, and means co-operating with the driving head to limit the travel of the pinion into meshed position, said inclined connection being so formed as to disconnect after a predetermined compression of the yielding member; including further an over-running clutch between the driving head and the inclined connection, and means including a spring for urging the pinion toward idle position and for maintaining the engagement of the over-running clutch.
